UNITED STATES PATENT OFFICE.

JOSEPH LEONARD, OF ALLENtown, PENNSYLVANIA, ASSIGNOR TO FIFTH AVENUE CORSET COMPANY, INC., OF ALLENtown, PENNSYLVANIA, A CORPORATION OF NEW YORK.

CORSET.

Application filed September 5, 1925. Serial No. 54,760.

My present invention is an improvement in the thigh reducer or controller feature of the type of corsets or corset brassières disclosed in my prior Patent 1,488,209, of March

25, 1924.

The principal object of my present invention is to provide a thigh reducer or controller in the nature of a belt connecting the lower sides of the garment together, such belt being adjustable independently of the adjustment of the garment and of the abdominal belt thereof, whereby the action of the thigh reducer is rendered independent of the abdominal belt, whereby the controller belt may be adjusted closely, while the garment and abdominal belt are adjusted loosely and vice versa, and whereby strains of movements of the thigh controller incident to the various postures of the figure are possible without transmission of undue strains to the garment and without affecting the adjustment of the garment or of the abdominal belt.

With these and other objects in view as will become more apparent as the description proceeds, the invention resides in the construction, combination, and arrangement of the parts hereinafter more fully described and claimed.

30 In the drawings:—

Figure 1 is a general view showing a corset brassière in which the invention is embodied.

Figure 2 shows the brassière opened and laid out flat.

35 Although I show and describe the embodiment of the invention in a corset brassière, it will be understood that the invention is equally applicable to a corset.

The garment in general, may be constructed 40 substantially as described in my prior patent, and in the description of the garment herein-after given, I will refer only to those portions which are necessary to give an understanding of the invention.

45 Referring more particularly to the drawings, the garment in general, includes a soft fabric outer portion 10 which completely encircles the body. At the sides of the body, the garment is split up to the waist line 50 W—L, and the adjacent edges on each side

of the splits are provided with eyelets 14, 14 and side lacing connections 15, 15. The elastic sections 16, 16 may overlie the upper portions of the split sides.

An abdominal belt 20 has eyelets 21, 21 at its ends through which the side lacing connections 15 pass for supporting the belt, the same lacings thus supporting the abdominal belt which connect the edges of the garment on each side of the splits together, as shown in my prior patent. As therein also set forth, the ends of the belt are connected with the side lacing connections at such points higher up or lower down as is found most suited to the wearer.

55 My prior patent shows elastic thigh sections set in the front adjoining the lower edges of the splits, to provide necessary yielding points when the wearer is seated, and causing the corset to fit the body at a 60 lower point. My prior patent further shows the outer edges of the elastic thigh sections as being connected to the adjacent edges of the split sides by the same lacings which 65 connect the edges of the split sides of the garment together.

70 My present invention departs from this prior construction with respect to the thigh section.

According to my present invention the 75 thigh controller or reducer, indicated generally at 22, is in the nature of a belt, the ends of which may be connected to the sides of the garment, further around to the sides than the split edges 23 thereof, as for instance, by rows of stitches 24. Thus the end portions of the thigh controller belt 80 overlie the lower portions of the split side portions of the garment, and are disconnected from these lower side portions save 85 at the vertical rows of stitches 24, and at the horizontal lower rows of stitches 25 which may be used to connect the lower edges 90 of the ends of the belt to the lower edges of the garment as shown. The thigh controller 95 belt thus forms a continuation of the lower portions of the garment. This belt is divided, preferably at the middle, as at 26, and the sections 27—28 of the belt thus formed, 100 may be connected together by adjustable

fastening means such as lacings 29. The upper edge of the thigh controller belt preferably is gradually concaved as at 30, and the lower edge preferably more sharply 5 concaved as at 31.

Elastic inserts 18 are set into the lower portions of the belt 22, and are preferably triangular in shape, being bounded on the one side by the downwardly converging 10 edges 32 of the non-elastic central portion of the belt, and on the other side by the downwardly diverging edges 33 of the non-elastic end portions of the belt. The elastic inserts 18 preferably extend up somewhat 15 beyond the medial horizontal line of the belt. By this construction, elasticity is given to the lower portion of the controller belt, this elasticity increasing as the lower edge of the belt is approached, while the upper portion 20 of the belt is non-elastic, but is pliable.

The controller belt is so disposed that its upper portion will overlie the lower portion of the abdominal belt 20, in ordinary positions of adjustment of the latter. The 25 front portion 34 of the garment to which the supporter tabs 35 are connected, in turn overlies the thigh controller belt, and tapers downwardly from the lower ends of the series of eyelets 14.

From the foregoing it will be observed 30 that the controller belt forms a continuation of the lower side portions of the garment, that its upper edge and its lower edge are disconnected from the garment, that it is 35 adjustable in length, that it has an increasing elasticity as its lower edge is approached, that it overlies the abdominal belt and underlies the front skirt portion of the garment, and that its edges are concaved. It 40 is to be understood that while I recite these features, I do not intend to imply that all or a combination of any particular one or more of them is essential to the invention, it being my purpose by such recitation 45 merely to clearly set forth the description of the particular embodiment of the invention herein shown.

Some of the advantages that may be noted 50 as accruing to my invention are as follows:—

The adjustment of the thigh controller belt is independent of the adjustment of the sides of the garment and of the abdominal belt and the controller belt may be adjusted 55 closely, at the same time that the abdominal belt or the sides of the garment are adjusted loosely, and vice versa. Further, by having the controller belt form a continuation of the sides of the garment, a greater 60 area is afforded in the thigh controller in taking up strain due to the change in positions, and the resultant effect of transmitting the strains in less degree to the garment. Further by having the controller belt unconnected from the front portion of

the garment, the smoothness of line of this part of the garment is increased, the belt being substantially hidden beneath the front portion of the garment when in use, and movements of the belt in conforming to the 70 positions of the figure take place beneath the front portion of the garment, and hence the lines of the garment are not disarranged incident to such movements. By having the ends of the controller belt set further 75 around towards the sides than the split edges of the side portions of the garment, and being free from said such split edges, greater range for the vertical independent adjustment of the abdominal belt is provided, 80 and again such pull as is transmitted to the lower portion of the garment by close adjustment of the controller belt is transferred further around towards the sides of the garment, and hence tends towards a more constant 85 smoothness of the lower back portion of the garment, as well as the front thereof.

I have illustrated a side opening garment, but it will be understood that the invention 90 is equally applicable to garments which open otherwise than at the side, for instance, at the front or back.

The foregoing description has been given for clearness of understanding, and no undue 95 limitations should be deduced therefrom, but the appended claims should be construed as broadly as permissible, in view of the prior art.

Having thus described my invention what I claim as new, and desire to secure by 100 Letters Patent is:—

1. A corset having a body portion provided with a front skirt portion, the sides of the body portion extending down along the thighs of the wearer, a thigh controller belt 105 which extends below the abdomen and forms a continuation around the thighs of the lower side portions of the garment and disposed beneath and being disconnected from said front skirt portion, said belt being divided, and connections adjustably connecting the sections of the belt together. 110

2. In a corset, the combination of a body portion, the lower sides of which are split, thereby forming a back portion and a front 115 skirt portion, both of which extend down along the thighs of the wearer, an abdominal belt extending around the abdomen of the wearer and connected to the back portion of the garment, and a thigh controller belt extending over the thighs of the wearer, and forming a forward continuation of the lower side portions of the garment, such thigh controller belt overlying the lower portion of the abdominal belt 120 and underlying the front skirt portion of the garment, and being disconnected from both. 125

3. In a corset, the combination of a body portion, the lower sides of which are split, forming a back portion and a front skirt 130

portion, both of which extend down along lower side portions of the garment, such as the thighs of the wearer, an abdominal belt extending around the abdomen of the wearer, and a thigh controller belt located 5 lower down than the abdominal belt and extending over the thighs of the wearer and forming a forward continuation of the

thigh controller belt underlying the front skirt portion of the garment and being disconnected therefrom.

In testimony whereof I hereunto affix my signature.

JOSEPH LEONARD.
